[57] CLAIM

The ornamental design for a portable word processor, as shown and described.

DESCRIPTION

FIG. 1 is a top, front, right side perspective view of a portable word processor showing my new design with the cover in a closed position;

FIG. 2 is a top plan view thereof on an enlarged scale;

FIG. 3 is a bottom plan view thereof on an enlarged scale;

FIG. 4 is a front elevational view thereof on an enlarged scale;

FIG. 5 is a rear elevational view thereof on an enlarged scale;

FIG. 6 is a left side elevational view thereof on an enlarged scale;

FIG. 7 is a right side elevational view thereof on an enlarged scale;

FIG. 8 is a front perspective view thereof on an enlarged scale with the cover in an opened position.
